UNITED STATES PATENT OFFICE

2,254,930

BURNER FOR LIQUID FUEL

James L. Breese, Santa Fe, N. Mex., assignor to Oil Devices, Santa Fe, N. Mex., a limited partnership of Illinois

Application September 11, 1937, Serial No. 163,371

3 Claims. (Cl. 158—91)

My invention relates to a heating device or burner and is applicable to burners for liquid hydrocarbons.

One purpose is the provision of means for controlling the temperature of the bottom of a so-called pot type hydrocarbon burner in which a liquid hydrocarbon is delivered to a mixing chamber having apertured walls and is there mixed with air, combustion taking place above or in the upper portion of the chamber.

Another purpose is the provision of means for directing a cooling flow of air against a portion or wall of such a chamber.

Another purpose is the provision of means for controlling the flow of the cooling air and for thus varying the temperature conditions at the bottom of the pot or chamber.

Other purposes will appear from time to time in the course of the specification and claims.

I illustrate my invention more or less diagrammatically in the accompanying drawing wherein:

Figure 1 is a vertical section; and

Figure 2 is a section on the line 2—2 of Figure 1.

Like parts are indicated by like symbols throughout the specification and drawing.

Referring to the drawing, 2 are angle iron frame members herein shown as forming a square or rectangle with the supporting legs 3 at the corners. The frame members 2 support an outer casing 1. 4 are transverse supporting members upon which is seated the burner proper which in the particular form herein shown includes a base member generally indicated as 5. The base member has a more or less concave bottom portion 6 surrounded by the cylindrical upwardly projecting wall 7 from which outwardly projects the circumferential flange 8. 9 is a centering flange upwardly projecting from the flange 8. The upper edge of the wall 7 is circumferentially channeled as at 10.

11 indicates a lower closure member or shield spaced beneath the burner base member 5 and supported by any suitable means. It is centrally apertured as at 14 about the lower enlargement or fuel inlet 15 of the base 5 to which is connected the fuel line inlet pipe 16. The circumferential flange 8 of the burner member 5 is provided with air inlet apertures 17.

Mounted on the flange 8 and centered by the flange 9 is the outer drum 20. Seated in the channel 18 is the inner drum 21 which is provided with a number of primary air apertures 22 and has about its upper edge a single row of

upwardly and inwardly inclined secondary air apertures 23, herein shown as of greater diameter than the primary air apertures. Seated on the upper edge of the drum 21 and extending outwardly over the upper edge of the drum 21 is the closure ring 24 with the lower centering flange 25 and the upper centering flange 26. Positioned thereupon and centered by the flange 26 is the upper drum 27 which forms a combustion and radiation chamber.

The particular unit herein shown is a circulating heater although my invention may be employed with other heaters. I illustrate as mounted on the channels 2 an outer housing formed of metal sheets 1. I may employ any suitable means to supply fuel to the bottom portion 6 of the burner, the fuel being supplied for example along the line or fuel inlet pipe 16.

In the use of my device, air admitted through 20 the aperture 14 flows directly against the bottom of the member 6 and has a cooling effect. The greater the circulation of air against the bottom of the burner the cooler the bottom becomes. In order to vary the temperature on the 25 bottom of the burner I provide means for increasing or decreasing the size of the air inlet 14. I illustrate a pair of overlapping slide valve members 50, 51, each being actuated by a rod 52 passing through a guiding eye 53 and having an exterior manually controlled end or handle 54. The members 50 and 51 have their opposed edges indented as at 55, 56 whereby as they are moved toward or away from each other a central aperture 57 is formed of controllable diameter. When 30 the members 50 and 51 are thrust as close as possible together, the aperture 57 is almost entirely occupied by the fuel inlet pipe 16 and there is but very slight space for air. When they are withdrawn from each other a maximum possible distance the entire aperture 14 is exposed.

It will be realized that whereas I have described and shown a practical and operative device, nevertheless many changes may be made in the size, shape, number and disposition of parts without departing from the spirit of my invention. I therefore with my description and drawing to be taken as in a broad sense illustrative or diagrammatic rather than as limiting me to my precise showing.

It will be understood that in addition to the specific details involved, what is of primary importance in my invention is the fact that I control the temperature of the mixing chamber wall or bottom 6 by controlling the flow of cooling air thereagainst. This is of practical importance

for example in controlling the capacity of the stove when employing a given grade of fuel. If the cooling effect of the air is reduced, the decrease of the cooling effect causes the bottom member 6 to become hotter. This in turn causes a greater vaporization of the liquid hydrocarbon and a greater capacity or heating effect for the unit. Thus the heating effect can be to some extent varied by varying the temperature of the mixing chamber or a portion of the wall thereof.

A further point of utility rests in the fact that where the user wishes to burn a lower grade of oil he can do so by diminishing the cooling effect of air and thereby increasing the temperature of the member 6. Thus in practice I find that controlling and varying the cooling effect of the air current renders my unit more flexible both in the range of fuel it can operate upon and in the capacity of the unit when operating upon a given fuel.

In the operation of the device, it will be understood that the volume of air which actually passes through the burner or mixing chamber itself is controlled by the cross sectional area of the primary and secondary apertures 22 and 23. The air passage to the burner is unrestricted and it is the total area of the primary and secondary apertures which meters the air. It is characteristic of my invention, however, that some or all of the air supplied to the burner is also employed to vary the temperature of the burner chamber itself and particularly of the burner bottom in such fashion as to vary the rate of evaporation or vaporization of the liquid hydrocarbon.

In considering the aperture 14 as the means for directing a flow of air against the burner or mixing chamber bottom 6, it will be understood that if the hole 14 were as large as or larger than the diameter of the burner, the air supply for the burner would pass through this large hole and up through the apertures 17 without having any substantial cooling effect on the bottom 6. Therefore, I employ an aperture of somewhat smaller diameter than the burner itself and in this aperture I place the valve means shown and described above. As the aperture is gradually decreased in its cross-sectional area, more and more air is forced to pass rapidly over the bottom of the burner. This rapid flow of air has a scrubbing effect and tends to carry away more and more heat. The greater the scrubbing effect, the lower the heat of the member 6 and the lower the rate of evaporation of the liquid hydrocarbon.

However, the aperture 14 is of such size and the valve members are so proportioned that the valve members 50, 51 of Figure 2 never restrict

the amount of air that will normally pass through the primary and secondary air apertures 22 and 23. In effect what I do is to vary the scrubbing or cooling effect of the air current which flows directly across the lower surface of the member 6. As the aperture is restricted the flow and scrubbing effect increase across the face of the member 6. As the aperture is increased in cross sectional area, the speed of flow across the surface 6 itself is lowered and the scrubbing effect is decreased without, however, varying or changing the supply of air to the burner itself.

It will be understood, of course, that in practice there is an ascertainable minimum closure which varies with the size and shape of the particular unit involved.

I claim:

1. In a hydrocarbon burner, a mixing chamber, means for delivering a liquid hydrocarbon to the interior thereof, means for delivering a stream of air upwardly against the bottom of said mixing chamber generally along the central axis of said mixing chamber, and means for varying the cooling effect of said stream of air, including means for varying the speed of movement of the air as it passes across the bottom of said mixing chamber.

2. In a heater, a mixing chamber having a bottom portion and a side portion, the side portion having formed therein a plurality of air apertures, a housing surrounding said mixing chamber, the interior of said housing being in communication with said air apertures, means for delivering liquid fuel to the upper face of said bottom portion, and means for delivering air to the interior of said housing, including a passage member adapted to deliver air against the lower face of the bottom portion of the mixing chamber, said passage member being aligned with the center of the mixing chamber, and means for varying the cross sectional area of said passage member while maintaining it substantially concentric with the center of the mixing chamber.

3. In a hydrocarbon burner, a chamber, means for supplying liquid hydrocarbon to the interior thereof, a housing enclosing the chamber, an aperture in the housing wall whose axis is intersected by the wall of the chamber, means for positively controlling the effective area of the aperture to control the flow of air inwardly therethrough, the distance between the apertured wall of the housing and the underside of the mixing chamber wall being such that the chamber wall directly receives the full force of the jet of air entering through the aperture immediately in line therewith.

JAMES L. BREESE.
